UNITED STATES PATENT OFFICE

JOSEPH GEORGE JACKSON, OF CHICAGO, ILLINOIS, ASSIGNEE TO EDWARD KATZINGER COMPANY, OF CHICAGO, ILLINOIS, A CORPORATION OF ILLINOIS*

CRACKER PAN

Application filed March 3, 1927. Serial No. 172,431.

The present invention relates to cracker pans and other such like devices, and has for its primary object to provide an improved frame structure for such devices which will enhance the durability of the device, cheapen its construction, and otherwise improve the same.

For the purpose of illustrating the salient features of the invention, two embodiments 10 are shown in the accompanying drawings in which

Fig. 1 is a plan view of the preferred embodiment;

Fig. 2 is a longitudinal section on the line 15 2—2 of Fig. 1;

Fig. 3 is an enlarged detail section looking in the direction of the arrows 3—3 in Fig. 1 and showing the preferred form of the frame joint;

Fig. 4 is a plan view of a modified form of the pan;

Fig. 5 is a longitudinal section on the line 5—5 of Fig. 4 looking in the direction of the arrows; and

Fig. 6 is an enlarged detail view, in section, of a modified form of the frame joint.

Referring now to the drawings in detail, the cracker pan comprises a supporting surface 5, preferably made from wire mesh, 30 screen, or mesh cloth, with a frame 6 for stretching the cloth, binding its edges and reinforcing the same. The present invention is concerned with the frame structure and according to the preferred form, as illustrated 35 in Figs. 1 to 3, inclusive, the frame is constructed of a plurality of elbow sections, each comprising a folded U-shaped band iron cut and bent into the proper form and adapted to be joined together to make up the frame.

The edges of the wire mesh 5 are confined 40 between the folds 7 and 8 of the U-shaped band irons and rivets 9 are employed to anchor the screen between the folds. These rivets pass through the folds 7 and 8 and through the mesh of the screen.

In order that the pan may be slid or otherwise moved over a supporting surface, or in fact over any surface, it is desirable that the faces 7 on each section of the frame on one side of the pan be flush with the faces on ad-

jacent sections. The same arrangement is also preferred for the opposite side of the pan in connection with the faces 8. To this end the joints between the sections are made flush and not even the heads of the rivets 9 project above the faces, the same being countersunk in the faces for this purpose. 55

So far as concerns the preferred form of joint shown in Figs. 1 to 3, inclusive, I arrange the ends of the sections in abutting or 60 at least confronting relation to one another as at 10 and to reinforce the joint, reinforcing members 11 and 12 are inserted between the folds 7 and 8 at the joint, the member 11, for instance, overlying the screen 5 on one 65 side and the member 12 overlying the screen on the opposite side. The members 11 and 12 preferably comprise metal strips of a width equal to that of the width of the folds of the sections and when inserted, as described, they 70 may be anchored by the rivets 9 passing through the folds of the sections, the members themselves, and the wire screen 5. In this construction the joints are properly reinforced and the sections rigidly held together with their faces flush. The joints are 75 preferably made to occur at the sides and ends of the frame so that the corners of the structure are not weakened by the joints.

Practically the same advantages so far as 80 rigidity and reinforcement is concerned may be accomplished by the modified form of the invention shown in Figs. 4 to 6, inclusive. In this form a so-called telescopic joint is provided by inserting the end of one section 6' 85 between the folds of an adjacent section, the screen 5' in this form having its edges bound between the folds of the frame sections as in the other form referred to. Rivets 9' are used in this form in the same capacity as in 90 the preferred form and their heads are countersunk in the faces of the folds. To realize a continuous flush face the opposite sides of the pan in this telescopic form of joint, I compress the folds to a smaller 95 dimension on the inserted section so as to compensate for the thickness of each fold on the outside section. This provides the countersunk portion clearly shown as at 13. The rivets 9' are preferably arranged so that 100

at least two rivets are to be provided for each joint at the ends of the telescoping sections. The frame sections 6' are also made as elbows, so to speak, so that the joints will occur at the ends and sides of the pan so as not to weaken the corners.

Due to the expanse of the wire screen and the more or less rough usage that cracker pans are usually subjected to, the edges of the wire screen tend to become loosened from the outer frame to which the wire screen is secured. However, by providing a U-shaped metal band to constitute the outer securing frame the ends of the wires cannot project from the frame into positions where such wire ends might injure the hands of the users. It should also be noted that the joints are intermediate the corners and therefore the corners of the frames may be kept in stock with the legs of varying lengths so that cracker pans of varying sizes, as desired, may be quickly and readily made by cutting the wire screen of the desired shape and size and then selecting from stock the corner frames with legs of lengths to fit the screens that have been cut. Therefore by means of the construction shown and described the corners and edges of the cracker pan will always present smooth surfaces to the hands of the users and at the same time the frame will be strong and durable, the joints being reinforced, as shown, for both forms. In other words, by properly reinforcing the joints and providing integral corner frames a cracker pan is provided which is strong and durable and may be subjected to hard usage without becoming distorted and without displacing any of the ends of the wires into any positions where they would come into contact with the hands of the users. Furthermore, the reinforcements at the joints and the means of securing the frame sections to each other and to the wire screen are such as to provide flush surfaces to permit the cracker pan to slide freely over the oven floor and other surfaces on which the cracker pan is placed and moved about. It will also be seen that the construction is such as to necessitate a minimum amount of material, thereby lessening the cost of construction and lightening the same to facilitate its use without sacrificing strength and durability.

Obviously those skilled in the art may make various changes in the details and arrangement of parts without departing from the spirit and scope of the invention as defined by the claims hereto appended and I wish therefore not to be restricted to the precise construction herein disclosed.

Having thus described and shown embodiments of my invention, I desire to secure the following by Letters Patent of the United States:

1. A cracker pan embodying in its con-

struction a wire screen and a frame therefor, said frame comprising a plurality of frame sections each U-shaped in cross-section and L-shaped in plan, means confining the cut edge of the wire screen between the folds of the frame sections so as not to be exposed, means comprising strip members inserted between the folds on opposite sides of the wire screen between the corners of the frame to form reinforced joints between the adjacent ends of the said frame sections, and rivets passing through the folds to permanently secure the wire screen to the frame and permanently secure said strip member at the joints.

2. A cracker pan embodying in its construction a wire screen and a frame therefor, said frame comprising a plurality of elbow sections each U-shaped in cross-section to form inwardly extending grooves to receive the peripheral edge portion of said wire screen while the latter remains in a single plane, and means comprising pairs of plates within said grooves on opposite sides of the wire screen for securing the elbow sections together with their exposed faces flush with one another.

In testimony whereof I have signed my name to this specification on this 28th day of February, A. D. 1927.

JOSEPH GEORGE JACKSON.
